United States Patent Office

Des. 174,331
Patented Mar. 29, 1955

174,331

ORGAN OR SIMILAR ARTICLE

Adolph D. Lambach, Woodland Hills, Calif., assignor to Thomas J. George

Application March 1, 1954, Serial No. 29,256

Term of patent 3½ years

(Cl. D56—2)

To all whom it may concern:

Be it known that I, Adolph D. Lambach, a citizen of the United States, residing at Woodland Hills, in the county of Los Angeles and the State of California, have invented a new, original, and ornamental Design for an Organ or Similar Article, of which the following is a specification, reference being had to the accompanying drawing in which the single figure is a perspective view of an organ incorporating my new design.

I claim:

The ornamental design for an organ or similar article, substantially as shown.
